HYDRAULIC MOTOR

Benjaman J. Pugh, Hamilton, Mont.

Application May 18, 1938, Serial No. 208,658

11 Claims. (Cl. 103—55)

This invention relates to improvements in hydraulic motors and more particularly to water motors of the type designed to utilize the force of a flowing stream to create power.

One of the objects of the invention is to provide a water motor of relatively simple, inexpensive and practical construction, and one which is not liable to get out of order.

Another object is to supply a hydraulic motor 10 of the reciprocating vessel type so constructed, that each bucket will travel its full stroke, whether ascending or descending, in order to eliminate any liability of the vessels halting midway of their strokes due to substantially equal 15 amounts of water being trapped in the two vessels.

A further object is to furnish a water motor in which the force of the water rushing out of either vessel will function to control a gate 20 which in turn controls the supply of water alternately to the vessels.

A still further object is to provide a hydraulic motor, each vessel of which has an outlet valve 25 in the form of a relatively large gate arranged at the bottom portion of the vessel to permit rapid discharge of water from the vessel.

With the foregoing objects outlined and with other objects in view which will appear as the description proceeds, the invention consists in 30 the novel features hereinafter described in detail, illustrated in the accompanying drawings and more particularly pointed out in the appended claims.

In the drawings:

Fig. 1 is a front elevation of my improved 35 hydraulic motor.

Fig. 2 is a top plan view of the same.

Fig. 3 is a vertical sectional view taken on the line 3—3 of Fig. 2.

Fig. 4 is a plan view of a portion of a modification of the invention.

Referring first to Fig. 2, it will be noted that the motor is supplied with flowing water by means of a trough 5 having outlet branches 6 and 7. The passage of the water through the branches is controlled by a valve or gate 8 pivotally mounted at 9 to swing about a vertical axis; the pivot post having oppositely extending arms 10 and 11 which are actuated by means 45 hereinafter described, in order to move the gate and divert the water from one branch to the other branch and vice versa.

The branches terminate at the upper end of a frame-work 12 forming adjacent vertical shafts 50 13, each provided at its corners with angular

guides or tracks 14 which constrain vessels 15 and 16 to move in vertical paths. The vessels are alternately filled with water and lowered from an uppermost position to a lowermost position. 5

Any suitable means may be employed to cause the rise of an empty vessel as the other filled one descends. For example, a walking beam 17 may be pivotally mounted at 18 at the top of the frame for movement about a horizontal 10 axis, and the ends of the beam are pivotally connected at 19 to supporting rods 20; the lower ends of the rods being secured by pivotal connections 21 to the bottoms of the vessels.

Another rocking beam 17a is pivotally mounted 15 at 18a on the frame of the machine and its ends slidably engage the bottoms of the vessels so that downward thrust of each vessel is resisted or balanced by the other vessel.

The front wall 22 of each vessel is provided 20 with a relatively large outlet or discharge port that is closed by a gate 23 hinged at 24 to the lower end of the front wall.

Each gate is held for a certain time in closed 25 position by any suitable means, such as a latch 25, which may consist of a lever 26 pivotally connected at 27 to the bottom of the vessel. As the point of pivoting is nearer the hooked front end 28 of the lever than its opposite end 29, the latter functions as a weight to normally hold 30 the latch in closed position. However, as the bucket descends, the end 29 will strike an abutment or bar 30 at the rear of the shaft with the result that the hooked end 28 of the lever will move downwardly to release the gate 23. 35

In order to utilize the force of the water discharged from the vessels to shift the gate 8, any suitable means may be employed to operatively connect the gates 23 to the arms 10 and 11. For example, a rigid arm 31 may be rigidly secured to each gate 23. Each arm is pivotally connected at 32 to the lower end of a rigid link 33 that is guided vertically by a guide bracket 34 rigidly secured to the front wall of the vessel. Guide pulleys or sheaves 35 and 36 are mounted respectively on the front walls of the vessels and on the top of the frame 12, and a rope or cable 37 extends from each arm, 10, 11, about a pair of these sheaves and has its forward end connected at 38 to the upper end 40 of the guide link 33. Owing to this construction, it will be understood that when a vessel is in its uppermost position, the cable 37 which is connected to its gate 23, will be slack, and afterwards when the vessel descends, the slack will 45 50 55

be taken up. At the time the vessel reaches its lowermost position, the slack will be entirely taken up, and as soon as the gate 23 is unlatched, water rushing out of the vessel will 5 swing the gate upwardly with the result that the cable 37 will pull forwardly on the arm 10, 11, with which it is connected so as to shift the inlet gate 8 beyond dead center, at which time the current flowing through the trough 5 will 10 act to complete the shift of the gate 8 so as to divert the water through the proper branch to the empty vessel which is now in raised position.

The power created by the motor may be utilized in any suitable way. For instance, I propose 15 to arrange upstanding pump cylinders 40 immediately below the vessels to co-act with plungers 41 arranged at the lower ends of the rods 42 which depend from the bottoms of the vessels. The lower ends of the cylinders are supplied with 20 the fluid to be pumped, by means of inlet pipes 43 having intake valves 44. The pumped fluid passes from the cylinders into discharge pipes 45, each having a discharge valve 46. The pipes 45 are connected to a common discharge pipe 47 that leads the pumped fluid to a suitable point 25 of storage or utilization. Due to my construction, it will be appreciated that the pumped fluid may be elevated by the pumping apparatus.

To insure closing of the outlet gates 23 as the 30 vessels ascend, I arrange suitable stationary abutments 48 on the front tracks 14. As the vessel rises, its gate will come into contact with the abutments, and the gate will thus be forced into closed position where it will be latched by the latch 25.

35 In operation, it will be assumed that the apparatus is placed in a flowing river or stream, the surface of which will be below the upper ends of the pump cylinders 40, provided the apparatus is not protected by a surrounding wall. Of course, if the apparatus has a surrounding wall, the apparatus may be arranged at a lower level. In either event the trough 5 will extend upstream to a point sufficiently far to gather the water, the weight of which is to be utilized in operating 40 the motor. With the parts in the positions shown, the water will flow through 5 and 7 into the vessel 16, and as soon as enough liquid has been deposited in that vessel to overcome the weight of the empty vessel 15, vessel 16 will start 45 to descend, and water will flow into the same until it reaches its lowermost position. Then its latch 25 will be actuated by means of the abutment bar 30 to release its gate 23, the latter opening as the water gushes out of the vessels. As the 50 gate rises, it will pull on the cable 37 with which it is associated, with the result that the arm 11 will be pulled forwardly to shift the inlet gate 8 so as to divert the stream through the branch 6 into the vessel 15 which reached uppermost position 55 when the vessel 16 reached lowermost position.

If the apparatus is built sufficiently large to enable the vessels to hold great amounts of water, I prefer instead of employing a single pumping cylinder 40 for each vessel to use four pumping cylinders 50 as indicated in Fig. 4. These cylinders will be arranged beneath the corners of each vessel and they will function not only as shock absorbers but as guide means to keep the vessel level while it is descending.

70 While I have illustrated and described the preferred embodiments of the invention in such manner that the same may be readily understood by those skilled in the art, I am aware that 75 changes may be made in the details disclosed

without departing from the spirit of the invention as expressed in the claims.

What I claim and desire to secure by Letters Patent is:

1. A hydraulic motor of the character de- 5 scribed, comprising a plurality of vessels, means for guiding the vessels and for causing each to rise as the other descends, means supplying water to the vessels when in uppermost position, valve means controlling the last-mentioned means for causing the water to flow to one vessel while it is in uppermost position and for cutting off the supply of water at that time to the other vessel, a discharge valve for each vessel opening in the direction of outward flow of water from the vessel, 15 and means operatively connecting the discharge valves to said valve means for causing shifting of the valve means by a discharge valve each time the discharge valve of each vessel is opened.

2. A hydraulic motor of the character de- 20 scribed, comprising a plurality of vessels, means for guiding the vessels and for causing each to rise as the other descends, means supplying water to the vessels when in uppermost position, valve means controlling the last-mentioned means for 25 causing the water to flow to one vessel while it is in uppermost position and for cutting off the supply of water at that time to the other vessel, means for discharging water from each vessel when it is in lowermost position, and means actuated by wa- 30 ter discharged from each vessel and operatively connected to said valve means for causing shifting of the valve means to alternately supply water to the vessels when they are in uppermost position.

3. A hydraulic motor of the character de- 35 scribed, comprising a plurality of vessels, means for guiding the vessels and for causing each to rise as the other descends, means supplying water to the vessels when in uppermost position, valve means controlling the last-mentioned means for 40 causing the water to flow to one vessel while it is in uppermost position and for cutting off the supply of water at that time to the other vessel, a swinging gate valve for controlling the discharge of water from each vessel, and means operatively 45 connecting the gate valve to said valve means for causing shifting of the valve means each time the gate valve of each vessel is opened.

4. A hydraulic motor of the character de- 50 scribed, comprising a plurality of vessels, means for guiding the vessels and for causing each to rise as the other descends, means supplying water to the vessels when in uppermost position, valve means controlling the last-mentioned means for causing the water to flow to one vessel 55 while it is in uppermost position and for cutting off the supply of water at that time to the other vessel, a relatively large discharge port for each vessel, a swinging gate for closing each port, and means operatively connecting the gates to said 60 valve means for causing shifting of the valve means each time the gate of each vessel is opened.

5. A hydraulic motor of the character de- 65 scribed, comprising a plurality of vessels, means for guiding the vessels and for causing each to rise as the other descends, means supplying water to the vessels when in uppermost position, valve means controlling the last-mentioned means for causing the water to flow to one vessel while it is in uppermost position and for cutting off the supply of 70 water at that time to the other vessel, an outwardly opening discharge valve for each vessel, means operatively connecting the discharge valves to said valve means for causing shifting of the valve means by a discharge valve each time the 75

discharge valve of each vessel is opened, and means for positively closing the discharge valve of each vessel as the latter rises.

6. A hydraulic motor of the character described, comprising a plurality of vessels, means for guiding the vessels and for causing each to rise as the other descends, means supplying water to the vessels when in uppermost position, valve means controlling the last-mentioned means for causing the water to flow to one vessel while it is in uppermost position and for cutting off the supply of water at that time to the other vessel, a relatively large discharge port for each vessel, gates closing said ports, each gate being hingedly connected to its respective vessel for swinging movement about a horizontal axis, and means operatively connecting the gates to said valve means for causing shifting of the valve means each time the gate of either vessel is opened.

20 7. A hydraulic motor of the character described, comprising a plurality of vessels, means for guiding the vessels and for causing each to rise as the other descends, means supplying water to the vessels when in uppermost position, valve means controlling the last-mentioned means for causing the water to flow to one vessel while it is in uppermost position and for cutting off the supply of water at that time to the other vessel, a relatively large discharge port for each vessel, gates closing said ports, each gate being hingedly connected to its respective vessel for swinging movement about a horizontal axis, means operatively connecting the gates to said valve means for causing shifting of the valve means each time the gate of either vessel is opened, and stationary abutments arranged in the paths of movement of the vessels and adapted to contact the gates to positively close the gates when the vessels ascend.

40 8. A hydraulic motor of the character described, comprising a plurality of vessels, means for guiding the vessels and for causing each to rise as the other descends, means supplying water to the vessels when in uppermost position, valve means controlling the last-mentioned means for causing the water to flow to one vessel while it is in uppermost position and for cutting off the supply of water at that time to the other vessel, a rigid arm rigidly connected with each discharge valve, guide links connected to said arms, oppositely extending arms connected to the valve means, guide sheaves, and cables extending about said sheaves and having their ends con-

nected respectively to the last-mentioned arms and to said links.

9. A hydraulic motor of the character described, comprising a plurality of vessels, means for guiding the vessels and for causing each to rise as the other descends, means supplying water to the vessels when in uppermost position, valve means controlling the last-mentioned means for causing the water to flow to one vessel while it is in uppermost position and for cutting off the supply of water at that time to the other vessel, an outwardly opening discharge valve for each vessel, means operatively connecting the discharge valves to said valve means for causing shifting of the valve means by a discharge valve each time the discharge valve of each vessel is opened, stationary pumping cylinders, each pumping cylinder having a valved inlet and a valved outlet, plungers arranged to reciprocate in the cylinders, and means operatively connecting the plungers to the vessels for forcing fluid from the cylinders each time a vessel descends.

10. A hydraulic motor of the character described, comprising a plurality of vessels, means for guiding the vessels and for causing each to rise as the other descends, means supplying water to the vessels when in uppermost position, valve means controlling the last-mentioned means for causing the water to flow to one vessel while it is in uppermost position and for cutting off the supply of water at that time to the other vessel, an outwardly swinging discharge gate for each vessel, and means operatively connecting the last-mentioned gates to said valve means for causing shifting of the latter each time a discharge gate of a vessel is opened.

11. A hydraulic motor of the character described, comprising a plurality of vertical shafts arranged side by side, a plurality of vessels guided by said shafts, means operatively connected to the vessels for causing each to rise as the other descends, a trough having branches for leading water to the upper ends of the shafts, a swinging gate for controlling the flow of water from the trough to the branches to cut off the flow through one branch while permitting the water to flow into the other and vice versa, an outwardly swinging gate for controlling the discharge of water from each vessel, and means operatively connecting the last-mentioned gates to the first-mentioned gate for causing shifting of the latter each time a discharge gate of a vessel is opened.

BENJAMIN J. PUGH.
